UNITED STATES PATENT OFFICE.

CHARLES E. DRESSLER, OF NEW YORK, N. Y.

DYNAMO-ELECTRIC MACHINE.

SPECIFICATION forming part of Letters Patent No. 498,537, dated May 30, 1893.

Application filed October 6, 1891. Serial No. 407,829. (No model.)

To all whom it may concern:

Be it known that I, CHARLES E. DRESSLER, of the city of New York, in the county and State of New York, have invented certain new 5 and useful Improvements in Dynamo-Electric Machines and Motors, which invention is fully set forth and illustrated in the following specification and accompanying drawings.

The object of this invention is sufficiently 10 indicated by its title.

The invention will first be described in detail and then particularly set forth in the claims.

In the accompanying drawings—Figure 1, is a 15 longitudinal sectional elevation of the machine showing it connected so that it may be used either as a dynamo or as a motor. Fig. 2 is an end view of Fig. 1, looking to the right, the part to the left of Fig. 2 being shown out of line 20 with the center of said figure for the purpose of clearer illustration. Fig. 3 is an enlarged view, detached, of one of the field-magnets shown in the preceding figures. Fig. 4 shows a modified detail of parts and connections, 25 hereinafter described.

In said figures the several parts are indicated by reference numbers and letters as below described.

The number 1 indicates the base of the machine which may be made of any suitable material, preferably cast-iron. Mounted upon said base and secured thereto in any suitable manner are two short cylinders or rings 2, preferably of wrought iron. Upon the inner 35 periphery of said rings, bolted or otherwise secured thereto, are field magnets 3, also of wrought iron. These magnets are of spool form as shown in Figs. 1, 2 and 3. The spools are preferably elongated instead of circular 40 and are suitably wound with insulated wire 4, in any well known manner, in order to make them electro-magnets when a current of electricity is passed through said wire. Said magnets are preferably bored out, as 45 shown in Fig. 3, and, in the holes bored, hardened steel pins 5 are inserted, which pins after being electrically excited will retain residual magnetism and thus make the electro-field-magnets in part permanent magnets also. 50 By thus constructing the field-magnets, the machine will soon reach its maximum gener-

ative power without energizing the field from any external electrical source.

The field-magnets being thus complete, the armature is constructed as follows: Upon a 55 suitable shaft 6, preferably of steel, mounted in suitable end bearings (not shown) is secured a sleeve or annular core 7, of soft iron. Said core is divided into a central section and two end-sections at the points 8, which sections or portions are suitably secured together across the cuts or spaces 8, by non-magnetic fastenings so that all three sections of the core may revolve together. A convenient method of securing said sections together, is 60 to radially insert brass screws tapped half into one section and half into the other at the points or cuts 8, as shown by the dotted lines 9. The core 7 however may be made continuous or unbroken, but by dividing it 65 the tendency to generate eddy-currents between the induction coil and armature is lessened or prevented. The end-sections of the core 7 may be suitably secured to the shaft 6, so as to revolve with it, through or by means 70 of the short sleeves 10, of non-magnetic metallic material. The end-portions of said core 7 being thus securely fastened to the shaft 6, so as to rotate with said shaft, the middle portion of said core 7 will also rotate with 75 said shaft by the convenient insertion of the brass screws above mentioned—or by any other means that may be employed for the same purpose—if it be desired to have said portion rotate with said shaft. But it is 80 immaterial whether said middle portion rotates or remains stationary. It may be supported in place in any suitable manner—a certain insulation such as the spaces 8, or other insulation, being preserved between 85 said middle and end-portions. The non-magnetic screws mentioned, or equivalent non-magnetic means, if used, need not be of brass, but should be of some non-magnetic material. The quality of electric conductivity, 90 however, of such fastenings, while not desirable as such does not militate against their use, as none of them is in an electric circuit, each fastening being in contact only with the separated surfaces of two magnets. The 95 construction above described diminishes the tendency of the counter-electro-motive force 100

inductively generated in the coil 14, from reacting, so to speak, upon the armature pole-pieces, for as said coil tends to impart magnetism of opposite direction in the middle portion of core 7, such current, but for the insulating spaces 8, would in turn react upon the magnetism generated in the armature pole-pieces and, by opposing such magnetism, tend to diminish its force. Upon said end-sections of the core 7, are mounted and secured thereto the armature magnets or pole pieces 11, of the form shown in the drawings—preferably elongated spools like the field-magnets, but also preferably laminated, or built up into shape of soft plate-iron, instead of being made solid. These armature-pole-pieces 11, are wound with insulated wire 12, in a suitable and well known manner.

In order that the armature magnets or pole-pieces may be placed in position within the field-pole-pieces or magnets, one end armature-magnet is made so that it may be slipped into position and secured after the other end-magnet has been put in place. This is done to allow of the insertion, between the end-pole-pieces of both the armature and field, of the fixed spool 13, now to be described.

The spool 13, of non-magnetic material, is circular and may be secured to either the base-piece 1, or in the short cylinders or rings 2 of the field. The spool however may be secured to the armature core if desired and rotate with the armature. Said spool is wound with insulated wire 14, and as shown and operated is an "induction coil." Its electricity is "induced" that is, its wire is energized by the alternations in the polarity of the armature while the machine is in operation. The coil, as shown in the drawings is inductively and immediately excited by means of the magnetism induced in the middle portion of the core 7, across the spaces 8, by the end-portions of said core on which the armature-magnets or pole-pieces 11 are mounted.

On one end of the shaft 6, is mounted a pole-changer 15 which rotates with said shaft. Said pole-changer may be of any approved construction. It may also be fixed to revolve on a separate shaft, if desired. Two collectors or collecting rings 16, 17 are secured to the shaft 6. These rings may be used or dispensed with, according to circumstances, as hereinafter explained.

The several modes in which the machine may be operated will now be described. The field and armature magnets and the spool 13 having been suitably wound with insulated wire, so that each pole piece in succession shall be of opposite polarity, as indicated by the letters N, S, Figs. 1 and 2, the connections of the wires are or may be then made as follows:—The end-magnets 11 of the armature are connected in circuit by their wires 12, passing, as shown in dotted lines, through the annular space between the armature core 7 and the shaft 6—the free end of one wire being connected to the collecting ring 16 and

the free end of the other wire to the collecting ring 17. Each of these rings is then connected by short wire connections 18, 19, and 70 their branches to the bars of the pole-changer 15, as clearly seen in Fig. 1. The end field magnets are connected by their wires 4, whose free ends respectively connect with brushes *a*, *b*, which are set to have tangential contact 75 with the bars of the rotary pole-changer 15, as clearly seen in Fig. 1. As also seen in Fig. 1, the induction-coil wound upon the spool 13, has the free ends or terminals of its wire 14 brought opposite each other, the interposed 80 letters *x* indicating incandescent lamps which close the circuit between said terminals. In Fig. 4, a modification of this connection is shown. The ends of the wires 14, are connected to the brushes *c*, *d*, which touch the 85 collectors or collecting rings 20, 21 (shown in dotted lines in Fig. 1) connected by short wires 22, 23 and branches to the bars of the pole-changer 15, as clearly shown in Fig. 4.

The operation of the machine as a dynamo, 90 connected as shown in Fig. 1, is as follows:—When the shaft 6 is rotated, by any external source of power, the alternating current produced by the armature's rotation is changed by the pole-changer and energizes the field-magnets with a continuous current. At the same time the armature inductively energizes, by its alternating magnetism, the induction-coil 14, as hereinbefore described. This current so induced in said coil is well adapted 95 for lighting purposes and may be so employed, as shown in Fig. 1, or said current may be used for other work. Part of the current generated may, at the same time, be taken off 100 from the rings 16, 17, as an alternating current before reaching the pole-changer and used for lighting purposes or other work, as may be desired. If said rings be not so used, the induction-coil will still discharge its said office, but, it may be advantageous and, under some circumstances, a more economical 105 mode of operating the dynamo, to take the current in its two phases, from the machine—both from the armature, direct, and from the induction-coil as above described. 110

The operation of the machine, as a dynamo, connected as shown in Fig. 4, is as follows:—The alternating current induced in the induction coil 14, by the armature's rotation is used through the medium of the brushes *c*, *d*, 115 collecting rings 20, 21, wires 22, 23 and branches, pole-changer 15, brushes *a*, *b*, and wires 4 to energize the field-magnets with a continuous current. The wires 4, however, when desired, may be connected to a storage-battery to charge the same, or to do other external work requiring a continuous current. In this case, the field could be excited as shown in Fig. 1, (where the coil 14 is in a lamp 120 circuit) as hereinbefore explained. The work of the induction-coil, however, if desired, might be divided between exciting the field and simultaneously doing some kind of 125 external work. But if the field be excited,

not by the armature as shown in Fig. 1, but by the induction coil 14, as shown in Fig. 4, (the wires 18, 19, Fig. 1 being dispensed with) then an unchanged alternating current may 5 still be taken off from the collecting rings 16, 17, (Fig. 1) in the same manner as before explained, and used for lighting purposes or other work suited to such current. It will be observed that if the induction-coil 14 is 10 cured to revolve with the armature as hereinbefore described, the brushes *c*, *d*, and even the rings 16, 17, as mere means of connecting the pole changer with either the induction-coil or armature, may be omitted.

15 This machine may be converted from a dynamo into a motor by supplying it with either an alternating or a continuous current.

First, with an alternating current, the manner of operation as shown in Fig. 1, is as follows:—The collectors 16, 17, being put in circuit with the necessary current, part of said current will be converted into a continuous current in passing through the pole-changer 15 to the field-magnets 3; the remainder of 20 the current unchanged will energize the armature magnets 11, the alternations in this current effecting the necessary change of polarity in said magnets to effect the rotation of the armature. Whatever amount of 25 alternating current may be induced in the induction coil 14, by the armature's rotation, may be utilized as desired for any suitable work.

Second. If the current to be used be a continuous current, then it must be led by circuit to enter the pole changer 15, (Fig. 1) when one portion thereof will directly energize the field, and the other portion, changed by the pole-changer into an alternating current, will energize the armature, and perform its office, exactly as just described, where the alternating current directly entered the collectors 16, 17.

If connected as shown in Fig. 4, the machine is operated as a motor as follows:

First. With an alternating current, said current is led by circuit to enter the collectors 20, 21, whence part goes, through pole-changer 15, to energize the field as a continuous current. The remainder of the current, unchanged, passes through the coil 14 which then inductively energizes the armature with an alternating current and thereby effects the armature's rotation.

Second. If a continuous current be used it must be led by circuit through the brushes *a*, *b*, (Fig. 4) into the pole-changer 15. One part of the current unchanged will thus energize the field through the wires 4, with a continuous current, and the remainder of the current changed in passing through the pole changer will traverse the coil 14, which will thus, as before explained, inductively energize the armature with an alternating current and thus effect the armature's rotation.

When using the machine as a motor, if it be desired to energize the field by the induc-

tion-coil 14, the wires 18, 19, may be dispensed with and an alternating current put in circuit, into the collectors 16, 17, which current 70 will directly energize the armature. The armature will then inductively excite the induction-coil 14, which coil will in turn, through the pole-changer 15 and connections shown in Fig. 4, and as already described, energize 75 the field-magnets with a continuous current.

If a continuous current only were obtainable to run the machine as a motor, it would be preferable to excite the field with said current in the manner hereinbefore described, 80 instead of first causing this current to inductively excite the induction-coil 14, and then said coil to excite the field through a circuit therewith.

The pole-changer 15, is shown, for convenience, in Figs. 1 and 4 with its bars *n* projected upon a plane. The end-view in Fig. 2, however, shows it cylindrical, or of a ring shape, adapted to rotate on the armature shaft. Each alternate bar *n*, is connected in 90 circuit by wires *w*, in full lines, and *t* in dotted lines, thus forming two sets of bars, each set connected in separate series and each series alternately becoming plus and minus, or in other words, alternately changing the polarity of the current delivered. It will be observed therefore, that this pole-changer is not a "commutator." A series of mere collectors, such as constitutes a "commutator," acts to change an alternating into a continuous current 100 by delivering each alternation of current, having the direction bearing the plus or positive name, to one brush and each alternation having the opposite or negative name to another brush, so that a new circuit having a continuous or non-alternating character is thus established.

The pole-changer 15, shown in the drawings, by reason of its construction, while changing the current from alternating to continuous and vice versa, as hereinbefore explained, is a much less complicated device than a commutator and by its introduction between the induction coil 14 and the field as seen in Fig. 4, avoidance of sparking is secured. For, in such case the coil may excite the field by a high voltage current through the pole-changer, while the current taken directly from the armature, for lighting or other external work, may be a large ampère-current.

I do not confine myself to the special arrangement of an induction coil 14, between the end-pole-pieces 3 and 11. For, it is obvious that said pole-pieces may be placed nearer 125 together with an induction-coil on each outer side of them, or if but one set of said pole-pieces be used an induction coil may be placed on either side or both sides of them, without in any wise departing from my invention.

A compact self-contained machine (when used as a dynamo, either self excited or not) is thus provided whose relation of ampère to volt current can be nicely adjusted through

the intervention of the induction coil or coils, or considerably varied by the substitution of a coil or coils wound with more or less or heavier or lighter wire, without disturbing the 5 windings of the armature or field magnets. With but short connections between any of the parts for receiving or delivering currents, very ready divisions of the currents may also be effected. For instance (with but one simple pole changer) an alternating current may be taken direct from the armature, and one portion of this current utilized unrectified, and another portion, diverted through the pole-changer, to excite the field-magnets, as a 10 continuous current. A third current may be taken, through the same pole changer from the induction coil or coils and used as a continuous current to charge a storage battery or do other work requiring a continuous current. The compactness of this self-contained 15 rotary converter-machine still provides for and permits the shaft or core of the armature (either inductively, or otherwise, excited by the armature proper) to be utilized to inductively excite the coil or coils, while leaving provision and ample room for each armature and field pole piece to carry its own winding. The 20 construction likewise admits, mechanically, such proportions of parts and variations in 25 relative windings of parts as to obtain high 30 economic "efficiency" using the term efficiency in its strictly technical sense.

Some of the advantages of this machine operated as a dynamo may be summarized as 35 follows:

The armature can be rotated in either direction by belt or otherwise from any source of power without change in adjustment of any parts of the machine. Power can thus be conveniently taken from a revolving car-axle to 40 rotate the armature.

The machine, though generating an alternating current, excites its own field with a continuous current through the intervention 45 of a simple non-sparking pole-changer. The machine, also, while operating at a moderate speed, can charge a storage-battery with a continuous current by day, so that the battery may charge the field at night, while the 50 dynamo is running, and also keep the lights burning while the dynamo is at rest. The machine can also be readily converted into an efficient motor, and if the induction-coil be used in such case, some of the machine's

power may be thereby conveniently distributed, in electrical instead of mechanical form, for lighting or other external work, or for the internal work of exciting either the field or the armature, as hereinbefore fully explained.

Having thus fully described my said invention, I claim—

1. A field-pole piece, for a dynamo electric machine, composed of soft iron and provided with hardened steel pins inserted in holes in 55 said iron.

2. In an electric dynamo electric machine or motor, the combination of the following named elements within the machine, a series of radial field-magnets, a rotary armature consisting of a core and a series of radial magnets, and an induction coil helically wound, at right angles to the armature's axis, and located at the side of the armature magnets.

3. In an electric dynamo electric machine or motor, the combination of the following 75 named elements within the machine; end-field magnets; a rotary armature provided with end-magnets; and an induction coil located between the inner sides of said armature-magnets so as to be inductively excited 80 by magnetism in said armature's core, substantially as and for the purposes set forth.

4. In an electric dynamo electric machine or motor, the combination of field magnets, an armature provided with radial magnets a 85 pole changer, or commutating-device, and an induction coil or coils, surrounding the armature-core, in circuit with the pole changer and field magnets, so that while said coil or coils, are inductively excited by alternating currents, the field magnets receive a continuous 90 current, through the pole-changer, from said coil or coils, substantially as and for the purposes set forth.

5. In an electric dynamo electric machine 95 or motor, in combination with a field magnet or magnets, an armature provided with a core having a part thereof separated from its poles by interposed non-magnetic material and inductively excited by the magnetism generated 100 in said poles; and an induction coil or coils inductively excited by said part of said core, substantially as and for the purposes set forth.

CHARLES E. DRESSLER.
